UNITED STATES PATENT OFFICE.

THOMAS LANGDON RIVERS, OF MONTCLAIR, NEW JERSEY.

LOOP OR BAND FOR STRAPS.

SPECIFICATION forming part of Letters Patent No. 350,081, dated September 28, 1886.

Application filed January 26, 1886. Serial No. 189,851. (No model.)

To all whom it may concern:

Be it known that I, THOMAS LANGDON RIVERS, a citizen of the United States, residing at Montclair, in the county of Essex and State of New Jersey, have invented new and useful Improvements in Loops or Bands, of which the following is a specification, reference being had to the accompanying drawings.

My invention relates to improvements in loops or bands; and it consists of a single metallic loop provided on its inner faces with corrugations or teeth to take into the folded or meeting ends of a strap, to obviate stitching said parts together; and my said invention further consists of a supplemental band or loop cast or formed integral with the main loop, to confine the free end of a strap that is connected to a buckle, which buckle is secured to a strap that has its end folded over the cross-bar of the buckle and secured together by my improved loop, all as hereinafter more fully described, and particularly pointed out in the claims.

In the drawings, Figure 1 is a perspective view of my improved band or loop. Fig. 2 is a like view of the clamping-loop, having the auxiliary band for confining the free end of a strap. Figs. 3 and 4 are perspective views of the loops shown in Figs. 1 and 2 applied to straps and buckles, and Fig. 5 is a vertical transverse section through the loop shown in Fig. 2.

Referring to the drawings, in which like letters of reference denote corresponding parts in all the figures, A designates my improved loop, which is preferably made rectangular and cast or formed in a single piece of metal. The end walls of the loop are curved slightly, as shown, and provided with smooth inner and outer faces, and the inner faces of the side walls are provided with teeth or corrugations, as at a, to bind on the strap ends that are inserted therein, to rigidly secure the ends of a strap or other flexible connection without stitching the same, as has heretofore been generally done.

B designates a strap, that has one end thereof bent or folded over upon itself, as at b, to provide means whereby a buckle, ring, guide-loop, or any other suitable device may be secured in the folded end of the strap, and over

this strap and the folded end b thereof is adjusted my improved loop A. This loop is forced over the strap and its folded end to a position near the buckle, ring, &c., and the teeth or corrugations thereof bind on the outer faces of the strap, to clamp them together. It will be seen that I thus provide a device which can be quickly and expeditiously adjusted over a strap to confine the folded end thereof in place without stitching or otherwise permanently securing the same, and that the loop is securely held in place against disengagement by frictional contact between its opposing faces and the strap, while at the same time the loop does not injure the strap in any way and can be conveniently removed to permit the buckle, &c., to be taken out and replaced.

The loop A is cast over a core of proper form to provide the interior teeth or corrugations, and said main clamping-loop is provided with an auxiliary loop, C, that is also cast therewith. This auxiliary loop consists, essentially, of side or end bars, c, that project outwardly and upwardly from the main clamping-loop, and a cross-bar, c', connecting the end bars, so that an opening or space is left or provided for the passage of a strap, D, that is connected or secured with a buckle, d, secured in the folded ends b of the strap B.

My improved loop is simple, strong, and durable, is thoroughly effective for the purposes designed, is inexpensive and cheap of manufacture, and can be cast very rapidly.

I am aware that heretofore harness-buckles have been provided with a loop that secures the folded ends of a strap together without stitching or other securing means; but my invention is wholly distinct and separate from the buckle, which is secured in the folded ends of a strap to which my improved loop is applied, the loop being readily removable independently of the device secured in the folded end of the strap, to adapt buckles of any construction, rings, or loops, to be secured in the said strap, and interchangeable one with another. My improved loop can also be used to detachably connect the meeting ends of two straps or other suitable or flexible devices.

Having thus described my invention, what I claim as new is—

1. As an improved article of manufacture,

a loop for securing the meeting or folded ends of straps, formed of a single piece of metal, and having its longitudinal walls arranged parallel with each other and provided on their inner 5 opposing faces with a series of longitudinal corrugations or teeth, which bite upon the outer faces of the straps inclosed within the same, substantially as described.

2. As an article of manufacture, a loop cast 10 in one piece and having interior teeth or corrugations, and an extended auxiliary loop, substantially as described.

3. The combination of a strap, B, folded 15 upon itself, a buckle secured in the folded end of the strap, a main loop fitted over the strap

and its folded end, and provided with interior teeth or corrugations that bind on the straps, and an integral auxiliary loop extended out of the plane of the opening in the main loop, and a strap, D, connected to the buckle and having its free end confined in the extended auxiliary loop, substantially as described. 20

In testimony that I claim the foregoing as my own I have hereto affixed my signature in presence of two witnesses.

THOMAS LANGDON RIVERS.
